(57) CLAIM

The ornamental design of a workstation, as shown and described.

DESCRIPTION

This application claims priority pursuant to 35 U.S.C. §119 to European Union Community Design Application No. 002367086-0001, filed 10 Dec. 2013, in the Office for Harmonization of the Internal Market, now registered.

FIG. 1 is a front elevation view of the workstation;

FIG. 2 is a bottom plan view of the workstation;

FIG. 3 is a right side elevation view of the workstation;

FIG. 4 is a rear elevation view of the workstation;

FIG. 5 is a left plan view of the workstation;

FIG. 6 is a top plan view of the workstation; and,

FIG. 7 is an orthogonal view of the workstation.

The broken lines in the drawings form no part of the claimed design and are used only to illustrate unclaimed subject matter.
